UNITED STATES PATENT OFFICE

163,545

COMBINED FAUCET AND SOAP DISH

Albert G. Smolensky, Cleveland, Ohio

Application January 26, 1949, Serial No. 510

Term of patent 14 years

(Cl. D91—3)

To all whom it may concern:

Be it known that I, Albert G. Smolensky, a citizen of the United States, residing at Cleveland, in the county of Cuyahoga and State of Ohio, have invented a new, original, and ornamental Design for a Combined Faucet and Soap Dish, of which the following is a specification, reference being had to the accompanying drawings, forming part thereof.

Fig. 1 is a front elevational view of a combined faucet and soap dish showing my new design.

Fig. 2 is a top plan view.

Fig. 3 is an end elevation.

Figs. 4 and 5 are sections on the lines 4—4 and 5—5, respectively, of Fig. 3.

Fig. 6 is a section on the line 6—6 of Fig. 2.

The dominant features of my design reside in the portions shown in full lines.

I claim:

The ornamental design for a combined faucet and soap dish, as shown and described.

ALBERT G. SMOLENSKY.
